OIL BURNER

Original Filed May 23, 1924

UNITED STATES PATENT OFFICE.

JOSEPH S. PECKER, OF PHILADELPHIA, PENNSYLVANIA, ASSIGNOR OF ONE-HALF TO
PAUL BROWN, OF PHILADELPHIA, PENNSYLVANIA.

OIL BURNER.

Application filed May 23, 1924, Serial No. 715,303. Renewed October 25, 1927.

This invention relates to an oil burner for furnaces and the like.

The object of the present invention is to improve the construction of oil burners and to provide a simple practical and efficient oil burner of strong, durable and comparatively inexpensive construction designed for use within a furnace and to be substituted for the grate thereof to enable oil to be used as a fuel in the furnace.

A further object of the invention is to provide an oil burner of this character equipped with means for effecting a pre-heating of the oil and air without causing the oil to coke within the oil supply pipe and capable of thoroughly mixing the oil and air and of producing a maximum combustion of the fuel.

It is also an object of the invention to provide an oil burner having means for producing an approximately horizontal spiral movement of the flame and products of combustion for maintaining the same a maximum length of time within the lower portion of the furnace and thereby subject the water jacket of the latter to the intense heat of the burner for a maximum length of time before permitting the products of combustion to escape through the flue of the furnace to the chimney.

Another object of the invention is to arrange the oil supply pipe and the oil supply means so that the oil will be heated to an even temperature prior to being mixed with the air whereby a more uniform flame of intense heat is produced.

A further object of the invention is to enable a burner to burn with a clear smokeless flame when the same is turned down to maintain it lighted at periods when heat from the same is not required.

Another object of the invention is to provide a burner, the operation of which will not be impaired should the burner either get out of level or not be properly levelled when the same is installed in a furnace.

Also it is an object of the invention to provide means for collecting and draining off any excess of the supply of oil so that the

latter will be saved and may also be utilized for controlling the feed of oil to the burner.

With these and other objects in view, the invention consists in the construction and novel combination and arrangement of parts hereinafter fully described, illustrated in the accompanying drawings and pointed out in the claims hereto appended, it being understood that various changes in the form, proportion and minor details of construction, within the scope of the claims, may be resorted to without departing from the spirit or sacrificing any of the advantages of the invention.

In the drawings:

Figure 1 is a plan view partly broken away of an oil burner constructed in accordance with this invention.

Figure 2 is a central transverse sectional view of the same.

Figure 3 is a plan view of the combined distributor cap and baffle, the vanes of the lower face thereof being illustrated in dotted lines.

Figure 4 is a detail view of a portion of the inner sectional baffle plate.

Figure 5 is a similar view of a portion of the outer sectional baffle plate.

Figure 6 is a detail reverse plan view of one of the air regulating damper slides.

In the accompanying drawing in which is illustrated the preferred embodiment of the invention, 1 designates the base of the burner of circular form provided at diametrically opposite points with depending cylindrical air inlets 2 and mounted in a sheet metal pan 3 supported upon tubular bars 4 as clearly illustrated in Fig. 2 of the drawings.

In installing the burner, the grate of the furnace 5, is removed and the bars 4 are secured in the furnace to form supports for the pan 3 which in practice, is designed to be filled around the burner with asbestos, clay or other suitable refractory material. The burner and the pan are of circular form to conform to the configuration of the furnace, but the burner and the pan may be of rectangular, oblong or any other shape to

suit the furnace in which the burner is designed to be used. The base is provided with an outer marginal wall 6 having an upwardly extending flange 7 and outwardly extending horizontal ears 8 which support a dome 9 fitted against the exterior of the upwardly extending flange 7 and provided with outwardly extending horizontal ears 10 bolted or otherwise secured to the ears 8, and 10 adapted to be readily removed when the fastening devices 11 are taken out.

The depending cylindrical air inlets 2 are exteriorly threaded at their lower ends for the reception of a cap 12, provided with 15 air inlet slots 13 which are controlled by a damper 14 consisting of a disk provided with openings 15 and mounted for rotary adjustment on a central stud 16 of the cap to cover and uncover the openings 13 so that air inlet 20 openings of the required size may be provided to control the inlet of air into the burner. The base is also provided with vertical walls 17, forming baffles and spaced from the sides of the dome substantially the 25 width of the air inlet 2 and curved to conform to the configuration of and arranged in parallelism with the sides of the dome for causing the air entering the inlets 2 to pursue a curved course in their passage from 30 the air inlets to the center of the burner as indicated by the arrows in Figs. 1 and 2 of the drawings. The baffles 17 by causing the air to take a curved path around the burner insure a heating of the air before the same 35 reaches the center of the burner and the baffles have their ends spaced apart at diametrically opposite points to provide entrance spaces for the air. The center of the base forms a pocket or reservoir which is 40 adapted to contain cold air so that any cold air will remain in the pocket at the base and the warm air will pass upward to mix with the oil as hereinafter fully explained.

The dome 9 tapers upwardly and the walls 45 are curved upwardly and inwardly as clearly shown in Fig. 2 of the drawing. The top 18 of the dome is of annular formation to provide a central opening and it is concavo convex in cross section to present an upper 50 trough shaped or annular concave face. This annular trough shaped top which may of course, be rectangular or other shape in plan view to conform to the shape of a furnace, is provided at its inner portion with 55 an oil groove 19, in which the oil drops and which also constitutes a starting cup when lighting the burner. The top of the dome is provided at its lower face with a rib 20 which forms a shoulder to fit against the 60 curved walls 17 at the inner face thereof as clearly shown in Fig. 2 of the drawing.

The air passes upwardly at the center of the base and through a narrow annular space or passage between the inner edge of 65 the top of the dome and a lower substan-

tially inverted conical deflector 21 which is secured to an inverted approximately conical central section 22 of a distributor cap and baffle 23 of approximately concavo convex form located above the top of the dome 70 in spaced relation with the same and forming a mixing space between it and the top of the dome. The lower conical deflector 21 is provided with a central threaded opening 24 into which is screwed the inner end 75 of an oil supply pipe 25. The oil supply pipe 25 extends vertically through one of the air inlets and is provided with a horizontal approximately circular portion 26 extending nearly around the burner and terminating in a substantially L-shaped drop bend 27. The approximately L-shaped drop bend 27 is mounted upon a pedestal 28 formed integral with the base of the burner and disposed radially thereof and pierced 80 by bolts 30, which fasten brackets 31 to the pedestal. The brackets receive the drop bend and hold the oil supply pipe rigidly in position in the burner. The oil which may have a gravity or other feed passes upwardly 85 through the vertical portion of the oil supply pipe and enters the horizontal circular portion and then passes through the drop bend into a vaporizing space or chamber 31' between the lower conical deflector and the 90 upper conical portion of the combined distributor cap and baffle. The central inverted conical portion of the combined distributor cap and baffle is provided with curved vanes 32 extending upwardly and 95 outwardly from the apex of the said central portion 22 and adapted to cause the oil to take a spiral course and spread in the space between the lower conical deflector and the upper conical section or portion 22. 100 The conical deflector which may be provided at its periphery with a vertical or nearly vertical face has grooves 33 formed therein to provide outlet passages for the oil and these grooves terminate above the inner annular groove 19 of the top of the dome, so 105 that the oil will be discharged in the groove 19. The distributor cap and baffle 23 is provided with a depending annular flange 34, which fits the peripheral face of the 110 lower conical deflector and it constitutes an outer wall for the oil outlet grooves. The concave convex distributor cap and baffle 23 is supported upon the deflector 21 by lugs 35 formed integral with the central portion 115 22 and extending from the lower face of the same and fitting in corresponding recesses 36, in the upper face of the deflector 21 as clearly shown in Fig. 2 of the drawings. The distributor cap and baffle is provided 120 with a central polygonal wrench receiving boss 37 which with the interlocking lugs 35 and recesses 36, will enable the inverted conical deflector to be readily screwed on or off the inner upwardly extending thread- 125 130

ed terminal of the oil supply pipe. The recesses 33 are also adapted to receive a suitable tool to enable the conical deflector 21 to be screwed on or off the threaded end of the oil supply pipe independently of the baffle 23, and this distributor cap and baffle may be readily lifted off the lower conical deflector to afford access to the burner.

After the burner has been started, the heat will vaporize the oil as it is discharged into the groove 19, and the oil vapor will thoroughly mix with the air entering the mixing space between the top of the dome and the distributor cap and baffle. In order to afford an ample supply of heated air to the oil vapor to produce complete combustion, the top of the dome is provided with slots 38 arranged in annular sets or series which are located at different distances from the center of the burner and which are disposed in overlapping or staggered relation, so that a complete circle of ascending heated air will be afforded for causing combustion of the fuel vapor. The top of the dome is also provided with upwardly projecting nipples 39, adapted to discharge heated air into the space between the dome and the distributor cap and baffle to cooperate with the air admitted through the slots and through the passage around the conical deflector in producing complete combustion of the fuel vapor. Any number of the slots and nipples may of course be provided and the size and number will be proportioned by the character and capacity of the burner, so as to afford a maximum combustion of the fuel.

The distributor cap and baffle plate is provided at its lower face beyond its central conical portion with curved radial vanes 40 extending from the flange 34 to the periphery of the distributor cap and baffle and adapted to produce a circular swirling motion of the flame and products of combustion to cause the same to linger or dwell at the lower portion of the furnace and thereby retain the flame and products of combustion a maximum length of time within the lower portion of the furnace, and thereby subject the water jacket of the furnace to a maximum heating effect of the burner. This retarding or holding back of the products of combustion is also assisted by inner and outer parallel baffles 41 and 42 which are mounted upon and extend above the distributor cap and baffle 23. The baffles 41 and 42 are preferably sectional as shown and the inner baffle 41, which is seated in a recess of a rib 43, of the distributor cap and baffle consists of a lower cylindrical portion and an upper flared portion while the outer baffle 42 is of approximately truncated conical formation forming an inclined wall extending upwardly and inwardly from the walls of the furnace over the upper edge of the distributor plate and baffle to a point within a

short distance of the angle formed by the upper and lower portions of the inner baffle. The inner and outer baffles are spaced a short distance from each other to permit the upward passages of the products of combustion and the flared or inclined upper portion of the inner baffle 41 directs or deflects the products of combustion outwardly to cause the same to impinge against the walls of the furnace in their upward passage to the smoke flue. The outer baffle 42 is provided at its inner side with arms 44, which are notched at their lower ends to fit the peripheral edge of the distributor cap and baffle upon which the outer baffle is seated. The inner and outer baffles are removable and may be readily taken off with the distributor cap and baffle for cleaning the burner. The top of the dome at the outer trough portion is provided with a drain pipe 45 which is adapted to conduct away excess oil and prevent the same from overflowing the trough in the top of the dome. In practice, the drain pipe 45 will be connected by a pipe 46 with suitable means for cutting off the flow of the oil to the burner when there is a certain amount of excess or overflow so that should the burner when turned low become extinguished the continued flow of the oil will operate to cut off the supply of the same to the burner. Such means for controlling the flow of oil are common in burners of this type and as such devices are well known in the art, illustration thereof is deemed unnecessary.

The oil before reaching the deflector 23, is uniformly heated by the arrangement of the curved horizontal portion of the oil supply pipe directly beneath and adjacent to the top of the dome. The pipe is not subjected to the direct action of the flame and there is no liability of the oil coking and caking on the interior of the oil supply pipe and at the same time there is sufficient heat in the metallic parts of the burner to raise the oil and the air to the necessary temperature for proper combustion before the oil vapor and air mix in the space between the dome and the distributor cap. The air and the oil vapor mix as they enter the mixing space and the hot gases in their travel radially of the mixing space pass through a wall of heated air permitted by the slots 38 to enter the mixing space and complete combustion is thereby assured and this supply of heated air is augmented by the jets from the nipples 39. The channels formed by the vanes 32 as well as the grooves in the conical deflector may be readily cleaned by lifting off the distributor cap. These vanes 32 as well as the vanes 40 produce a circular or swirling motion so that the spreading of the oil and the mixing of the vapor and air are radiated most effectively in addition to the holding of the hot gases for increasing length of time in

the bottom portion of the furnace. Also, should the burner get out of level or not be in a proper level condition when installed, its effectiveness will not be impaired.

5 The space between the dome and the generating or vaporizing device formed by the deflector and the central portion of the distributor cap, may be varied by means of vertical adjusting screws 48 extending 10 through the bottom of the base and having their upper ends arranged in openings of lugs 49 formed integral with the vertical walls or partitions of the base and located at the upper edges thereof and extending 15 inwardly from the said walls or partitions as clearly shown in Fig. 1 of the drawing. The screws project below the base as illustrated in Fig. 2 and are adapted to be adjusted for raising and lowering the dome. 20 The said screws are preferably four in number, two being arranged at the inner faces of the said vertical walls or partitions and the adjustment is effected prior to the tightening of the bolts 11, which secure the dome 25 to the base. After the desired adjustment of the dome has been made to provide a circular air space around the deflector 21, the bolts 11 are then tightened and the dome is rigidly secured to the base. The upwardly 30 extending walls or partitions and the shoulders of the dome against which the upper edges of the partitions or walls fit permit this vertical adjustment within certain limits without in any way breaking the air chamber in the casing formed by the dome and the base. The vaporizer or generator device is formed by the deflector 21 and the central inverted conical portion of the distributor cap and provides the vaporizing 35 chamber 31' for vaporizing the oil to convert the same into either a vapor or gas, previous to mixing with the air the space 31' between the deflector 21 and the central inverted conical portion of the cap is designed 40 primarily for and operates as a vaporizer. 45

It will be seen that the casing formed by the dome and the base constitutes an air heating chamber and also incloses the oil supply pipe, and that one of the air ports 50 is utilized in bringing the cold oil from the exterior of the casing into the same to heat the oil before introducing it into the vaporizing and generating device and the heating of the oil will greatly facilitate the flow 55 of the same in its upward movement into the said device. The location of the oil pipe within the casing beneath the dome protects the oil pipe from direct contact with the flame of the burner and the oil pipe 60 while being heated does not come in contact with the said flame thereby eliminating baking and coking of the oil inside the pipe. The oil as it flows upwardly in the vaporizing and generating device comes in contact with 65 the distributor cap which, after the burner

has been started, becomes highly heated due both to the conduction of heat by the metal of the distributor cap and also by the heat conducted by the baffles or flanges depending from the lower convex face of the said cap. 70 The oil within the vaporizing and distributing device spreads out into a circular flow and drops downward through the slots and in coming in contact with the vertical face of the hot distributor cap becomes vaporized 75 and any portion of the oil escaping through the ports in an unvaporized condition is atomized and broken up across the rounded or beveled edge of the dome by the draft of heated air emerging from the central opening in the said dome. 80

The construction of the casing formed by the dome and the base is such that the air is positively heated before it can possibly escape and mix with the fuel vapors and the said air entering the casing is caused to take a curved passage around the same and there are no cross currents of air that can possibly interfere with the passage of the air around the casing and the heating of the air before it leaves the air chamber. The central opening through which the oil distributing and vaporizing device projects is unobstructed by projections and a uniform draft of air is permitted to pass through the space between the distributor cap and the dome. By the arrangement of air ports between the inner and outer edges of the top of the dome, no vapor or partially consumed oil is permitted to escape from the burner without being brought into contact with a sufficient supply of oxygen to produce complete combustion. The heavy rim or thickened inner edge of the dome at the central opening, serves to hold a relatively large amount of heat and as the air impinges against the enlarged inner edge or inner rim, it will be clear that the temperature of the air will be raised considerably just prior to the mixing of the air with the fuel vapor. 100

Also, the thickened top wall of the air dome and its increased capacity for holding heat serves to raise the temperature of the air within the casing at the top of the dome and around the oil pipe, which is arranged immediately beneath the top of the dome. 115

What is claimed is:

1. A burner including a base having an air inlet, a dome mounted upon the base and provided in the top with an opening, a superimposed distributor cap spaced from the opening to form an air passage and provided with means for discharging fuel adjacent the said passage to cause the same to mix with air, said dome being provided beyond the said opening with openings arranged to permit an upward flow of air. 125

2. A burner including a base having an air inlet, a dome mounted upon the base and 130

- provided in the top with an opening, a superimposed distributor cap spaced from the opening to form an air passage and provided with means for discharging fuel adjacent the 5 said passage to cause the same to mix with air, said dome being provided beyond the said opening with openings arranged to permit an upward flow of air, said openings being arranged to produce a continuous wall 10 of upward flowing air in the space between the dome and the distributor cap. 10
3. A burner including a base having air inlets and provided with means for controlling the passage of air through the same, a 15 dome mounted upon the base and cooperating with the same to form an air chamber, walls extending from the base to the dome in spaced relation with the sides of the latter to provide air passages, a superimposed distributor cap spaced from the dome to form an air outlet and to provide a mixing space 20 between the cap and the dome, said cap being provided with a fuel passage discharging at the space between the cap and the dome, and 25 means for supplying fuel to the distributor cap. 25
4. A burner including a base having a central pedestal, a dome mounted on the base and cooperating therewith to form an air 30 chamber said dome being provided with an opening, a superimposed distributor cap spaced from the dome at the opening to provide an air outlet, said cap being also provided with fuel passages discharging at the 35 space between the cap and the dome and a liquid fuel pipe extending into the base and having a horizontal portion extending around the dome below the top thereof, said fuel pipe being also provided with a branch 40 or portion mounted upon the pedestal and connecting the horizontal portion with the passages in the distributor cap. 40
5. A burner including a base, a dome mounted upon the base and cooperating 45 therewith to form an air chamber, said dome being provided in its top with an opening, a superimposed distributor cap spaced from the dome at the opening to provide an air outlet and having fuel passages discharging 50 at the space between the cap and the dome, the latter being provided beyond the fuel passages with a plurality of slots and nipples for the discharge of air into the said space, and means for supplying fuel to the distributor cap. 55
6. A burner including a base having a bottom and walls, a dome mounted upon the base and constituting a top wall for the same and forming an air chamber said dome being 60 provided at its top with an opening, a superimposed distributor cap spaced from the said opening to provide an air outlet thereat and extending over the dome in spaced relation therewith to form a mixing space and a combustion chamber and a mixing space beyond 65
- the outlet, said cap being also provided with fuel passages discharging at the air outlet, and means for supplying fuel to the said passages and curved vanes located in the mixing space to produce a circular swirling 70 movement of the gases. 70
7. A burner including a base having a bottom and walls, a dome mounted upon the base and constituting a top wall for the same and forming an air chamber and provided with an opening, a superimposed distributor cap of approximately concavo convex form spaced from the dome at the said opening to provide an air outlet thereat and extending over the dome to form a mixing 75 space and a combustion chamber and having curved vanes at its lower face to produce a curved swirling motion of the gases resulting from combustion, and means for supplying fuel to the space between the cap and the dome. 80
8. A burner including a base, a dome mounted upon the base and forming an air chamber and having an opening in its top, a superimposed distributor cap provided with a central inverted conical portion, an inverted conical deflector arranged at the central portion of the cap and spaced from the dome at the said opening to form an air outlet, a passage, being formed between the deflector and the central portion of the cap for fuel, means for raising and lowering the dome to vary the size of the air outlet, and means for supplying fuel to the said passage. 85 90
9. A burner including a base, a dome surrounding the same and having a central opening, a distributor cap provided with a central inverted substantially conical portion and having a depending flange surrounding the same, an approximately inverted conical deflector arranged within the said flange and spaced from the central conical portion of the cap and provided with peripheral grooves forming fuel discharge passages, means for raising and lowering the dome to vary the size of the said air outlet, and means for supplying fuel to the space between the deflector and the central portion of the cap. 95 100
10. A burner including a base, a dome surrounding the same and having a central opening, a distributor cap provided with a central inverted substantially conical portion and having a depending flange surrounding the same, an approximately inverted conical deflector arranged within the said flange and spaced from the central conical portion of the cap and provided with peripheral grooves forming fuel discharge passages, curved vanes arranged in the space between the deflector and the central portion of the cap to provide channels for fuel, and means for supplying fuel to the said space between the deflector and the cap. 115 120
11. A burner including a base provided 130

- with a bottom and walls and having a dome constituting a top wall to form an air chamber and provided in the top with an opening, a superimposed deflector cap spaced 5 from the opening to provide an air outlet thereat and extending over the dome to form a mixing space and a combustion chamber and having fuel passages discharging thereat, and inner and outer deflectors mounted 10 upon the distributor cap at the periphery thereof and arranged to deflect the gases inwardly and then outwardly.
12. A burner including a base provided with a bottom and walls having a dome constituting a top wall and surrounding the base and provided with an opening, a substantially concavo convex distributor cap spaced from the said opening to provide an air outlet thereat and extending over the 15 dome to form a mixing space and a combustion chamber and presenting a lower convex face, means for supplying fuel at the said space between the deflector cap and the dome, an outer inclined baffle mounted upon the periphery of the deflector cap, and an inner baffle also mounted upon the deflector cap and consisting of a lower vertical portion and an upper outwardly inclined or flared portion extending over the outer baffle. 20
13. A burner including a base provided with a bottom and walls having a dome constituting a top wall and forming an air chamber and provided with a central opening in its top, a superimposed deflector cap spaced from the dome to provide an air outlet thereat and extending over the dome in spaced relation thereto to form a mixing space and a combustion chamber, means for discharging fuel at the said space and means 25 for producing a circular or swirling motion of the gases formed by combustion in their outward passage through the said space.
14. A burner including a base provided with a bottom and walls having a dome constituting a top wall and forming an air chamber and provided with a central opening in its top, a superimposed deflector cap spaced from the dome to provide an air outlet at the top opening and extending over the dome to form a mixing space and a combustion chamber, means for discharging fuel at the said space and means for producing a circular or swirling motion of the gases formed by combustion in their 30 outward passage through the said space, and means for producing upward currents of hot air across the said space and at an angle to the direction of movement of the said gases.
15. A burner including a base provided with a bottom and walls having a dome constituting a top wall and forming an air chamber and provided with a central opening in its top, a superimposed deflector cap spaced from the dome to provide an air 35 outlet at the opening and extending over the dome to form a mixing space and a combustion chamber, means for discharging fuel at the said space and means for producing a circular or swirling motion of the gases formed by combustion in their outward passage through the said space, and means for producing upward currents of hot air across the said space and at an angle to the direction of movement of the said gases.
16. A burner including a casing forming an air chamber and comprising a base provided with walls and having air inlets at the bottom and a dome mounted upon the base and constituting a top wall and having a central outlet opening at the top, a distributor cap extending over and arranged in spaced relation with the dome to form a mixing space and a combustion chamber and having an oil distributing and vaporizing device spaced from the dome at the said central opening to provide an air passage, and means for adjusting one of the said parts towards the other to vary the size of the said air passage. 40
17. A burner including a casing forming an air chamber and comprising a base provided with walls and having air inlets at the bottom and a dome mounted upon the base and constituting a top wall and having a central outlet opening at the top, a distributor cap arranged in spaced relation with the dome and having an oil distributing and vaporizing device spaced from the dome at the said central opening to provide an air passage, vertical screws mounted in the casing and engaging the dome at the underside thereof for raising and lowering the dome to vary the size of the said air passage. 45
18. A burner including a casing forming an air chamber and comprising a base having air inlets at the bottom and a dome mounted upon the base and having a central outlet opening at the top, a distributor cap arranged in spaced relation with the dome to form a mixing space and a combustion chamber and having an oil distributing and vaporizing device spaced from the dome at the said central opening to provide an air passage, vertical walls or partitions rising from the base and arranged in overlapping relation with the dome for causing a circulation of air around the casing, said walls or partitions being provided at their upper portions with projecting lugs and adjusting screws piercing the base and mounted in the said lugs and engaging the underside of the dome for raising and lowering the same to vary the size of the said air passage. 50
19. A burner including a casing forming an air chamber and comprising a base having air inlets at the bottom and a dome

mounted upon the base and provided with a central opening at the top, a distributor cap spaced from the dome and having an oil distributing and vaporizing device at 5 the said central opening and spaced from the dome to provide an air passage, said dome being depressed to provide an oil receiving trough, a drain pipe extending from the said trough, a drain pipe section carried 10 by the base and having a loose coupling with the said drain pipe to permit an adjustment of the dome, and means for adjusting the dome to vary the size of the air passage between the distributing and vaporizing device and the dome.

20. A burner including a casing forming an air chamber and comprising a base provided with walls and having air inlets at the bottom, and a dome mounted upon the

base and constituting a top wall and having a central opening at the top, a superimposed distributor cap extending over the dome and spaced from the same to provide a mixing and combustion space and having an oil distributing and vaporizing device at 25 the said central opening of the dome and spaced from the dome at the opening to provide an air passage, and an oil pipe extending into the base through one of the air inlets thereof and provided with a curved portion 30 extending around the air chamber adjacent the top of the dome and connected with the said oil distributing and vaporizing device.

In testimony whereof I have hereunto set 35 my hand.

JOSEPH S. PECKER.
